CORE APPARATUS FOR FORMING ARCHED PIPE

Thomas D. McGinnis, Theodore W. Mohle, and William E. Nichols, Houston, Tex., assignors to Turtle Back Pipe Company, Houston, Tex., a corporation of Texas

Application March 26, 1957, Serial No. 648,694

14 Claims. (Cl. 25—128)

This invention relates to an improved apparatus for forming arched pipe of concrete or other hardenable plastic material. This application is a continuation-in-part of our co-pending application, Serial Number 541,918, filed October 21, 1955, and now abandoned.

One rather conventional procedure for forming round pipe of concrete or similar material is to pour the material in a plastic state into an annular space between vertically disposed inner and outer mold members and closed at opposite ends by pallets or end mold members, wherein it is permitted to harden. Since the inner mold member is not readily removable axially from the opening through the formed pipe, it has been the practice to provide such mold member with a separation along its length to permit it to be collapsed by reducing its peripheral length effective to define the diameter of the opening through the pipe.

When the concrete is poured into the space between the mold members from too great a height, there is a tendency for the aggregate to settle to the bottom and thus seriously weaken the pipe. As a result, both building codes as well as the industry itself have placed limitations upon this amount of "free drop" such that pipe formed by this method is necessarily in rather short sections. Also, when concrete is poured into upstanding mold members in this manner, it is impossible to observe the reinforcement and make sure that it is not shifted or jarred out of place.

Arched pipe is preferred over round pipe inasmuch as, for example, it requires less head room and less backfill. However, in order to take optimum advantage of the structural characteristics of the arch, the side of the opening through the pipe opposite the arch should define the maximum lateral dimension of such opening. That is, the arched portion of the pipe should not be permitted to curl back under at its lower side.

As in the case of round pipe, it is necessary in the forming of arched pipe to collapse the inner mold member prior to removing same. However, with the side opposite the arch defining the maximum lateral dimension of the mold member, it was found difficult to remove the inner mold member according to earlier techniques without injury to either the mold member or the formed pipe. That is, the mere reduction of the peripheral length of the curved portion of the mold member did not permit its collapse into a shape for removal.

It is an object of this invention to provide a mold for forming arched pipe of this type in sections of greater length than has heretofore been possible and, more particularly, in a manner which permits observance of the reinforcement during pouring of the concrete or other hardenable plastic material.

Another object is to provide an inner mold member for use in the formation of such pipe which is easily and readily collapsible for removal from the opening through the formed pipe without damage to either the mold member or the pipe.

Still another object is to provide a novel operator

2

for selectively expanding and collapsing an inner mold member of the character described in the foregoing object.

A still more particular object is to provide such an inner mold member with means for facilitating the lifting thereof.

Yet a further object is to provide pallets so constructed as to be particularly well suited for forming arched pipe of concrete or the like in accordance with the present invention.

Other objects, advantages and features of this invention will be apparent to one skilled in the art upon a consideration of the written specification, the attached claims and the annexed drawings.

In the drawings, wherein like reference characters are used throughout to designate like parts:

Fig. 1 is a perspective view of one form of mold constructed in accordance with this invention and including an inner mold member disposed in an expanded position within an outer mold member to define a space therebetween which is closed at opposite ends by pallets and into which concrete or the like may be poured in forming arched pipe;

Fig. 2 is a sectional view of the mold taken along broken line 2—2 of Fig. 1, and resting upon a horizontal support;

Fig. 3 is a perspective view of the inner mold member of Figs. 1 and 2 moved to a collapsed position within an arched pipe formed thereby, and with the outer mold member and pallets removed from the pipe for purposes of illustration;

Fig. 4 is another perspective view of the collapsed inner mold member of Fig. 3, but removed from the opening through the pipe;

Fig. 5 is an enlarged sectional view of the double hinge construction at one corner of the inner mold member of Figs. 1 to 4;

Fig. 6 is a perspective view of the spigot end of the formed pipe shown in Fig. 3;

Fig. 7 is an end view of another form of inner mold member constructed in accordance with this invention and disposed in expanded position within a formed pipe from which the outer mold member and pallets have been removed for purposes of illustration;

Fig. 8 is a view similar to Fig. 7, but with the inner mold member in collapsed position;

Fig. 9 is a perspective view of the collapsed inner mold member of Fig. 8 removed from the formed pipe;

Fig. 10 is an end elevational view of still another form of mold which is similar to, but an improvement upon, the form of Figs. 1 and 2; and

Fig. 11 is a longitudinal section view of the mold of Fig. 10, taken substantially along broken line 11—11 of Fig. 10.

According to the present invention, there is provided an apparatus for forming arched pipe of the type described wherein an inner mold member, expandable into a substantially rigid shape having a contour corresponding to the opening through the pipe, is supported in its expanded position substantially horizontally above a similarly disposed outer mold member to define a space therebetween corresponding to the thickness of the arch of the pipe. With the mold members so disposed, the space is filled and the flat side of the inner mold member is covered with concrete or the like to form the pipe with a minimum of "free drop" of the material.

That is, inasmuch as the material is poured into a horizontally extending space, the amount of drop is determined by the height of the pipe rather than its length so that such length may be materially increased.

The outer mold member is provided with an open side opposite its concave portion which permits observa-

tion of the reinforcement above the flat side of the inner mold member for the entire length of such mold members. As a result, movement of the reinforcement during pouring of the material may be corrected.

The inner mold member is supported in properly spaced relation to the outer mold member by means of pallets or end mold members through which the inner mold member is received. These pallets are releasably attachable to opposite open ends of the outer mold member and receive the inner mold member in such a manner as to tightly close the opposite ends of the space between the inner and outer mold members, and are further of such construction as to resist displacement of the inner mold member due to buoyancy of the concrete during filling of said space.

Further in accordance with this invention, the side of the expanded inner mold member which defines the maximum lateral dimension of the opening through the pipe is formed by a pair of flat sections which are abuttable with one another along their inner longitudinal edges and hingedly connected about their outer longitudinal edges to a curved portion of the mold member which defines the arch of the pipe. The curved portion includes means for reducing the lateral length thereof effective to define said arch, so that the inner longitudinal edges of the flat sections may be moved out of abutment and the outer longitudinal edges thereof moved inwardly relative to one another so as to reduce the width of the side effective to define the maximum lateral dimension of the mold member and thereby collapse the mold member to permit its removal from the opening through the pipe.

The lateral length of the curved portion of the inner mold member effective to define the arch of the pipe is reduced upon the collapse of a plurality of relatively movable sections which make up such portion. In accordance with a preferred form of inner mold member, these sections of the curved portion include a central curved section and a side section hingedly connected to each longitudinal edge of the central section and substantially perpendicularly to the flat sections. Thus, the width of the side effective to define the maximum lateral dimension of the mold member and the lateral length of the curved portion effective to define the arch of the pipe are reduced upon inward swinging of the side sections.

This preferred form of inner mold member is provided with a novel actuator for selectively expanding and collapsing same, which actuator comprises a toggle linkage connecting a flat section with the central curved section. The inner mold member is also provided with internal lateral bracing which supports a crank shaft for the toggle linkage as well as tubular parts at each end of said mold member adapted to receive a fork lift.

According to another form, the curved portion includes a pair of sections in abutment with one another along their inner longitudinal edges, such that upon movement of the inner longitudinal edge of one of the flat sections and one of the sections of the curved portion out of abutment with and inwardly with respect to the other section of each, as well as movement of the hingedly connected outer longitudinal edges of each inwardly toward one another, a similar collapsing effect as in the preferred form is accomplished to permit the removal of the mold member.

Referring now to the drawings, and particularly the preferred form of mold shown in Figs. 1 to 5, an outer mold member 20 having a substantially concave curved portion and open at its side opposite the curved portion may be provided with legs 21 or other means for supporting it in a substantially horizontal position, as shown in Fig. 2. A pair of pallets or end mold members 22 and 23 are releasably attached in any suitable manner to the opposite open ends of outer mold member 20 and provided with openings therethrough to receive the inner

mold member in properly spaced relation above the outer mold member 20. These pallets include flat and curved sections adapted to close opposite ends of such space and shaped to provide the formed pipe A with a bell end 24 (Fig. 3) and a spigot end 25 (Figs. 3 and 6), respectively.

The preferred form of inner mold member, designated in its entirety by the reference character 26, is shown in Figs. 1 and 2 in expanded position and received closely within the openings through pallets 22 and 23, and in Figs. 3 and 4 in a collapsed position to permit its removal from the opening through the formed pipe. As can be seen from the drawings, this inner mold member includes a curved portion 27 which defines the arch of the pipe to be formed, and a side 28 opposite the curved portion which defines the maximum lateral dimension of the mold member. The side 28 is formed by a pair of flat sections 29 and 30 which are connected in abutment with one another along their inner longitudinal edges by hinge 31. These sections are made of a substantially rigid and inflexible material, such as $\frac{3}{16}$ inch sheet steel, or otherwise braced by lateral ribs to prevent flexure under the weight and pressure of the concrete.

For the purpose of permitting its lateral length effective to define the arch of the pipe to be reduced, the curved portion 27 is made up of a central curved section 32 and side sections 33, such sections also being constructed to withstand the pressure of the concrete. The side sections are hingedly connected at 34 to the outer longitudinal edges of each of the flat sections 29 and 30 substantially perpendicularly to said flat sections, and also along their opposite edges to the longitudinal edges of central section 32 by means of hinges 35, such that the connected flanges of the two hinges form the section 33.

The hinges 34 and 35 are shown in more detail in Fig. 5, wherein it may be seen that as the side sections 33 are swung inwardly (counterclockwise) about hinge 35 and hinge 31 moves downwardly, the width of flat sections 29 and 30 which defines the maximum lateral dimension of the mold member as well as the lateral length of curved portion 27 of the mold member effective to define the arch of the pipe will be reduced, whereby the entire mold member is collapsed to the position shown in Figs. 3 and 4 to permit its removal from the opening through the pipe.

It should be noted with respect to the inner mold member 26 that the flat sections 29 and 30 are abuttable with one another in aligned relation so that the side 28 of the mold member is also flat. Although this is preferred from a structural standpoint, it is not essential. It should also be noted that the entire lateral length of curved portion 27 of the mold member need not define the curvature of the arch but rather, as indicated on a small scale by side sections 33, some of such portion may define a flat surface connecting the curvature defining the arch with the side 28 of the mold member. In this manner, the height of the pipe may be increased to any desired degree as long, of course, as the sections 29 and 30 are abuttable with one another to define the maximum lateral dimension of the mold member. In this same connection, it will be still further understood that the side sections 33 are hingedly connected to the flat sections 29 and 30 substantially perpendicularly thereto to permit them to swing inwardly about hinges 35 in the manner above-described.

With the inner mold member 26 expanded, and preferably held in expanded position by a plurality of vertical braces 36 spaced longitudinally thereof, it is disposed in a substantially horizontal position spaced above the similarly disposed outer mold member 20 in a manner previously described, so as to define an arched space 37 therebetween which is closed at opposite ends by end mold members 22 and 23. As indicated in Fig. 1, reinforcing rods 37a may be placed in predetermined spaced

relation within space 37 as well as above the side 28 of the inner mold member for a purpose well known in the art.

In accordance with the present invention, the concrete or other hardenable plastic material is poured in its plastic state into the space 37 and onto the side 28 of the inner mold member so as to surround same and form the pipe while the mold members are disposed in the above-described substantially horizontal position. Obviously, the material will fill the space and cover the side 28 of the inner mold member above a level corresponding to the upper edge of outer mold member 20 so that it may be troweled off to form a substantially smooth side on the pipe A, as shown in Figs. 3 and 6. Not only does this method of filling the forms reduce to a minimum the "free drop" of the material, but also it permits observance at substantially the entire period of such pouring of the spacing and placement of the reinforcing rods 37a.

When the material has hardened so as to form the pipe A which is shown in Figs. 3 and 6, the inner mold member 26 may be collapsed, in a manner previously mentioned, to permit to be moved freely longitudinally of the opening through the pipe. Obviously, such removal is accomplished without damage to either the mold member or the formed pipe since it is necessary to force neither. That is, the inner mold member is readily collapsed for removal and use in the forming of another pipe of the desired configuration. Although in Fig. 3, the outer end end mold members have apparently been removed prior to removal of the inner mold member, it should be understood that this is merely to better illustrate the formed pipe since it is the practice to remove the outer and end mold members subsequent to removal of the inner member.

The form of inner mold member shown in Figs. 7 to 9 and designated in its entirety by reference character 38 is shown in an expanded position within the opening through a just-formed pipe A in Fig. 7 and in a collapsed position in Figs. 8 and 9, the outer mold member being removed for the same reason as in Fig. 3. It will be understood, of course, that the arched pipe A may be formed in a manner described in connection with Figs. 1 to 5 with the use of an outer and end mold members similar to those shown in Figs. 1 and 2.

As in the case of inner mold member 26 of Figs. 1 to 5, inner mold member 38 is expandable into a shape having a curved portion 39 defining the arch of the pipe and a side 40 opposite the curved portion which defines the maximum lateral dimension of the mold member. The opposite side 40 is formed by a pair of substantially inflexible flat sections 41 and 42 each of which is abuttable with the other along its inner longitudinal edge and hingedly connected at 43 about its outer longitudinal edge with the curved portion 39. However, in contrast to the flat sections 29 and 30 of inner mold member 26, the abutting inner longitudinal edges of flat sections 41 and 42 are tapered in the direction of movement of one of said flat sections with respect to the other flat section between abutting and non-abutting positions. Thus, as can be seen from Fig. 8, the tapered inner longitudinal edge of flat section 41 is tapered inwardly and downwardly to permit it to be moved in a similar direction over the opposite edge of section 42 from the position of Fig. 7 to that of Fig. 8.

The curved portion 39 of inner mold member 38 includes a pair of curved sections 44 and 45 having inner longitudinal edges tapered for abutment, as shown in Fig. 7. As in the case of flat sections 41 and 42, the abutting edges of sections 44 and 45 are tapered in the direction of movement of one of said sections into and out of abutment with the other section. Thus, upon such movement of the inner longitudinal edge of section 44 over and out of abutment with the correspondingly tapered edge of section 45, the lateral length of curved portion 39 effective

to define the arch of the pipe is reduced to permit collapse of the inner mold member.

Each of the movable sections 41 and 44 is provided with a stop member 46 adjacent its inner edge adapted, in the expanded position of the mold member, to overlap the inner edge of the section with which it abuts. Not only does the part 46 serve as a means for aligning the edges of abutting sections, but also serves as a water seal for the seam or joint extending longitudinally of the mold member between the sections.

Each of the movable mold member sections 41 and 44 may be moved into and out of abutting relation with its adjacent section 42 and 45, respectively, by an operator 47 operable from one end of the mold member.

Each such operator 47 may comprise a rotatable crank 48 carried upon a support 49 attached to one of the mold member sections and extending longitudinally of the mold member to a point adjacent one end thereof for manual manipulation. Connecting the crank and movable section 20 is a link 51 and eccentric 50, the latter being rotatable with crank 48 and the link pivotally connecting the movable section and eccentric, such that rotation of the crank in one direction will serve to urge the movable section to an abutting and expanded position, while movement in an opposite direction will urge it to a collapsed position out of abutment with its adjacent section. Thus, as can be seen in Figs. 7 and 8, rotation of the crank 48 in a clockwise direction urges section 41 to an expanded position with its edge in abutment with that of section 42, while rotation in a counterclockwise direction urges section 41 out of abutment with section 42 for collapsing the side 40 of the mold member. Obviously, the opposite is true of the function of operator 47 for curved section 44 of curved portion 39 of the mold member.

Although the form of mold illustrated in Figs. 10 and 11 corresponds in its more basic aspects to the form of Figs. 1 and 2, it is an improvement thereover in a number of respects to which the description to follow will be principally directed.

As in the earlier described form, the outer mold member 55 of the mold of Figs. 10 and 11 includes a longitudinally extending portion 56 which is curved to the outer periphery of the arch of the pipe to be formed and open along each end as well as opposite its curved length. The curved portion 56 is supported upon spaced lateral plates 57 which are in turn carried above longitudinal runners 58 so as to dispose the outer mold member 55 with its open top uppermost, as shown in the drawings.

Each of the pallets or mold members 59 and 60 for the bell and spigot ends of the pipe is made up of an arched portion 61 and a flat portion 62 fixedly secured to the arched portion for defining an opening 63 therethrough to receive the expanded inner mold member 64. When the pallets are attached to the outer mold member 55 in a manner to support the inner mold member in properly spaced relation above the outer mold member, as will be described hereinafter, the flat portions 62 thereof fixedly secured to the arched portions 61 provide maximum resistance to raising of the inner mold member due to the buoyance of the concrete.

As can be seen from the drawings, the arched portions 61 of the pallets are formed oversize so that they may be attached across the open ends of the outer mold member 55 with their outer edges projecting concentrically outwardly of the curved portion 56. Thus, with the inner edge of said arched portions 61 curved to define the inner periphery of the arch of the pipe so as to closely fit the expanded inner mold member 64, the overlapping outer edges insure against leakage from the space between the inner and outer mold members by compensating for out-of-round in the latter.

The means for releasably attaching a pallet across an open end of the outer mold comprises a plurality of brackets 65, some of which are broken away in Fig. 10, spaced circumferentially about the end of the curved

portion 56 of the outer mold member to form slots 66 for holding the outer edges of the arched portion of each pallet in the overlapping position above mentioned. Screws 67 are received in the brackets 65 for forcing the outer edge so held against the ends of the curved portion 56 for closing the ends of the space. More particularly, the ends of the screws 67 are received within recesses 68 in the outer edge of each pallet, at least two of which screw ends and recesses are tapered for aligning the pallets circumferentially of the brackets.

The inner mold member 64 is very similar to its counterpart 26 in the mold form of Figs. 1 and 2 in that it includes a longitudinally extending curved portion 69 which defines the arch of the pipe to be formed, and a side 70 opposite the curved portion which defines the maximum lateral dimension of the mold member. Also, the side 70 is formed by a pair of flat sections 71 and 72 connected at their inner longitudinal edges by a hinge 73.

Still further, the curved portion 69 is made up of a central section 74 and side sections 75 hingedly connected along one edge at 76 to opposite longitudinal edges of the central section 74. The side sections 75 are hingedly connected along their opposite edges at 77 to the outer longitudinal edges of flat sections 71 and 72. Thus, when the inner mold member is expanded, as shown in Fig. 10, the side sections 75 will be disposed substantially perpendicular to flat sections 71 and 72, and the inner edges of said flat sections will be in abutment and aligned with one another so that the side 70 is flat.

As in the case of the first described form of mold, the inner mold member 64 is adapted to be collapsed or expanded by reducing or extending the lateral length of curved portion 69 thereof. In this improved form of mold, such collapse or expansion is accomplished by means of an operator 78 comprising a toggle linkage connecting a flat section, such as 72, with the central section 74 of the curved portion 69 for selectively swinging them toward and away from each other. More particularly, one link 79 of the linkage is pivotally connected to a lateral flange 80 on the flat section 72, and the other link 81 is connected to a crank shaft 82 journaled within lateral braces 83 on and spaced longitudinally of central curved section 74. As can be seen from Figs. 10 and 11, an arm 84 is provided on an outwardly extending portion of the shaft so as to rotate the shaft in a counterclockwise direction (Fig. 10) for actuating the toggle linkage to collapse the inner mold member.

More particularly, the shaft 82 extends through the entire length of the inner mold member for connection with a toggle linkage 78 at each end thereof so that the operator may be manipulated from either end.

A pair of tubular members 85 are fixedly secured to two or more of the outermost braces 83 for extension longitudinally inwardly of one end of the inner mold member a relatively short distance. These members 85 are of such an inner diameter and so spaced apart as to accommodate a fork lift for lifting inner mold members of substantial weight. The securement of the members 85 to two or more of the braces 83 distributes the stress on the inner mold member when lifted.

From the foregoing it will be seen that this invention is one well adapted to attain all of the ends and objects hereinabove set forth, together with other advantages which are obvious and which are inherent to the operation of the apparatus.

It will be understood that certain features and sub-combinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

The invention having been described, what is claimed is:

1. For use in the formation of arched pipe of concrete or other hardenable plastic material, an inner mold member expandable into a shape having a longitudinally extending curved portion defining the inner periphery of the arch of the pipe and a side opposite the curved portion which defines the maximum lateral dimension of the mold member, said opposite side being formed by a pair of flat sections in abutment with one another along their inner longitudinal edges and hingedly connected with the curved portion about their outer longitudinal edges, and said curved portion including means for reducing the lateral length thereof effective to define the arch of the pipe, whereby the inner longitudinal edges of the flat sections may be moved out of abutment and the outer longitudinal edges thereof moved inwardly with respect to one another to collapse the mold member and permit its removal from the formed pipe.

2. For use in the formation of arched pipe of concrete or other hardenable plastic material, an inner mold member expandable into a shape having a longitudinally extending curved portion defining the inner periphery of the arch of the pipe and a side opposite the curved portion which defines the maximum lateral dimension of the mold member, said opposite side being formed by a pair of flat sections in abutment with one another along their inner longitudinal edges, and said curved portion including, a side section hingedly connected to the outer longitudinal edge of each of the flat sections of the opposite side substantially perpendicularly thereto and a central curved section hingedly connected to the side sections, whereby the lateral length of the curved portion effective to define the arch of the pipe as well as the width of the opposite side effective to define the maximum lateral dimension of the mold member are reduced upon swinging of the side sections inwardly toward one another and movement of the inner longitudinal edges of the flat sections out of abutment.

3. A mold of the character defined in claim 2, including toggle linkage pivotally connected at opposite ends to one of said flat sections and said central curved section and operable for selectively expanding or contracting said inner mold member.

4. An inner mold member of the character defined in claim 3, wherein the pivotal connection at one end of said toggle linkage includes a shaft extending through the length of the inner mold member, and handles are attached to each end of the shaft for operating the toggle linkage at each end of the inner mold member.

5. For use in the formation of arched pipe of concrete or other hardenable plastic material, an inner mold member expandable into a shape having a longitudinally extending curved portion defining the inner periphery of the arch of the pipe and a flat side which defines the maximum lateral dimension of the mold member, said flat side being formed by a pair of flat sections hingedly connected together with their inner longitudinal edges in abutment with one another, and said curved portion including, a side section hingedly connected to the outer longitudinal edge of each of the flat side sections substantially perpendicularly thereto and a central curved section hingedly connected to the side sections of the curved portion, whereby the lateral length of the curved portion effective to define the arch of the pipe as well as the width of the opposite side effective to define the maximum lateral dimension of the mold member are reduced upon swinging of the side sections inwardly toward one another and the hingedly connected longitudinal edges of the flat sections downwardly and out of abutment with one another.

6. An inner mold member of the character defined in claim 5, including a series of flanges secured to the interior of the central curved section transversely to the inner mold member, a longitudinally extending crank shaft journaled within said flanges, a toggle linkage connecting said crank shaft to one of said flat sections, and

a handle for rotating the crank shaft from a location exteriorly of the inner mold member.

7. An inner mold member of the character defined in claim 6, including a pair of tubular members secured to at least certain of said flanges and extending longitudinally of the inner mold member, said members being so spaced apart and having openings therethrough of such size as to receive a fork lift.

8. For use in the formation of arched pipe of concrete or other hardenable plastic material, an inner mold member expandable into a shape having a longitudinally extending curved portion defining the inner periphery of the arch of the pipe and a side opposite the curved portion which defines the maximum lateral dimension of the mold member, said opposite side being formed by a pair of flat sections in abutment with one another along their inner longitudinal edges and hingedly connected with the curved portion about their outer longitudinal edges, said curved portion also including a pair of sections in abutment with one another along their inner longitudinal edges, such that upon movement of one of the sections of each of the opposite side and the curved portion out of abutment with and inwardly with respect to the other section, the lateral length of the curved portion effective to define the arch of the pipe and width of the opposite side effective to define the maximum lateral dimension of the mold member are reduced to collapse and permit removal of the mold member from the formed pipe.

9. An inner mold member of the character defined in claim 8, wherein the abutting inner longitudinal edge of the one section of each of the opposite side and curved portion movable inwardly of the other section thereof is tapered in the direction of such movement.

10. An inner mold of the character defined in claim 9, including an operator having a crank operable from one end of the mold member for moving the movable section of each of the opposite side and curved portion into and out of abutment with the other section thereof. 35

11. For use in the formation of arched pipe of concrete or other hardenable plastic material, an inner mold member which includes, a longitudinally extending curved portion comprising a plurality of relatively movable sections expandable to define the inner periphery of the arch of the pipe and collapsible to reduce the lateral length of the portion effective to define the arch, and a pair of flat sections hingedly connected about their outer longitudinal edges to the sections of the curved portion for expansion therewith into abutment with one another along their inner longitudinal edges to define the maxi- 40 45 50

mum lateral dimension of the mold member, said inner longitudinal edges of the flat sections being movable out of abutment and the outer longitudinal edges thereof being movable inwardly toward one another upon collapse of the curved portion sections to permit reduction of the width of the flat sections effective to define the maximum lateral dimension of the mold member and removal of the mold member from the formed pipe.

12. An inner mold of the character defined in claim 10, wherein the relatively movable sections of the curved portion include a central curved section, and a side section hingedly connected to each longitudinal edge of the curved section and substantially perpendicularly to the flat sections, whereby the curved portion is collapsible upon swinging of the side sections inwardly with respect to one another.

13. An inner mold of the character defined in claim 11, wherein the relatively movable sections of the curved portion include a pair of sections in abutment with one another along their inner longitudinal edges, such that upon movement of one of the flat sections and one of the sections of the curved portion out of abutment with and inwardly with respect to the other section of each, the lateral length of the curved portion effective to define the arch of the pipe and width of the flat sections effective to define the maximum lateral dimension of the mold member are reduced to collapse and permit removal of the mold member from the formed pipe.

14. An inner mold of the character defined in claim 12, wherein the abutting inner longitudinal edges of the flat sections are hingedly connected together for swinging movement out of abutment in response to said inward swinging of the side sections.
